Architectural tie rods are frequently used in concrete work to hold form boards in place. These rods are usually made of small diameter rods and are secured to the form boards by means of a tie holding device. After the concrete has set, these rods are usually withdrawn from the concrete by means of a tie puller. The tie puller is usually a long bar with a pair of jaws at one end and a handle at the other end. The jaws are usually formed of a pair of spikes or barbs which grip the tie rod and the handle is used to pull the tie rod out of the concrete.

UNITED STATES PATENT OFFICE

TIE PULLER

James C. Mushet, Roselle Park, N. J., assignor, by mesne assignments, to Ralph E. Ogden, New York, N. Y.

Application June 8, 1942, Serial No. 446,316

4 Claims.

(Cl. 254—18)

This invention relates to a tie puller for pulling form ties or tie rods from concrete after the concrete has set.

In the so-called architectural type of concrete work tie rods of small diameter are utilized and are pulled out after the concrete has set, thus leaving relatively small holes to be patched or filled in. The concrete having set tightly grips the tie and considerable effort and force are required to loosen and withdraw the tie rod.

This invention has for its salient object to provide a concrete tie puller that is simple in construction, effective in operation and can be economically manufactured.

Another object of the invention is to provide a device of the character described that can be used to loosen as well as to pull tie rods.

Further objects of the invention will appear from the following specification taken in connection with the drawing which forms a part of this application, and in which

Fig. 1 is a sectional elevation illustrating a concrete form and tie rod for holding the form in place;

Fig. 2 is an enlarged elevational view illustrating the tie puller;

Fig. 3 is a transverse sectional elevation taken substantially on line 3—3 of Fig. 2; and

Fig. 4 is an elevational view showing the tie puller in operation pulling the tie.

In the particular embodiment of the invention shown there are illustrated form boards 10 and 11 which are held in place by a tie rod 12, it being understood that a plurality of tie rods is used.

The tie rods may be of any desired construction and as shown each tie rod has a pair of heads at each end, the heads being indicated at 13 and 14. The rods extend through openings 15 and 16 in the form boards 10 and 11 and between spaced vertical beams or studs 17 and 18 and spaced horizontal beams or walers 19 and 20.

The ties are held in position by spreaders or clips 25 which are secured over the rods adjacent the collars 13 and by wedges 26 which are driven over the outer end portions of the rods adjacent the outer heads or collars 14. The construction of the clips 25 is not material to the present invention but these clips may be formed with an elongated member 27 having a notch extending thereinto from one edge and a hinged closure member 28.

Furthermore, it should be understood that the particular construction of form tie and of the holding means therefor has nothing to do with the present invention.

The tie puller of this invention is a relatively simple device which is particularly adapted for use in architectural type concrete work. It consists of an elongated rod or shank 30 having secured to one end a foot or shoe 31 consisting of a bar secured to and extending transversely of the end of the rod or shank 30. This bar has preferably formed thereon a pair of barbs or spikes 32.

The rod 30 has slidably mounted thereon a head 33 which fits loosely on the rod or shank and is provided with a laterally extending forked end or claw 34.

The other end of the rod or shank 30 has a head 35 formed on or secured thereto. Intermediate the fixed head 35 and the sliding head 33 there is slidably mounted a relatively heavy handle 36.

When the concrete has set, the wedge 26 and spreader 25 are removed and the puller is applied as shown in Fig. 4. From this figure it will be seen that the form tie has been cut outside of the sheathing on the left side of Fig. 4 and the puller is shown engaging the outer head 14 on the right hand side of the figure. The sliding head 33 is in contact with the foot bar 31. This foot bar is placed across the walers 19 and 20, spanning the space between them, with the spikes 32 engaging the two walers and the claw 34 engaging the outer head 14 of the tie.

By the lever action of the bar 30 the tie is withdrawn step by step by moving the sliding head away from the foot bar until the tie is fully loosened in the concrete. The sliding head is then moved back into contact with the foot bar and the withdrawal completed by the jarring action of the handle 36. This jarring action may be used in unison with the lever action in the position shown in Fig. 4 to start the tie.

It will be evident that the head 33 can be moved successively outwardly on the rod 30 and when the rod is moved in a direction to cause the claw to press forcibly against the head engaged thereby, there will be a slight tilting action between the rod and the head causing the rod to tightly engage the head at the points designated X and Y on Fig. 2.

The barbs or spikes 32 on the bottom of the cross bar or foot or shoe 31 engage the walers 19 and 20 and prevent the tool from slipping.

Although one specific embodiment of the invention has been particularly shown and described, it should be understood that the invention is capable of modification and that changes

in the construction and in the arrangement of the cooperating parts may be made without departing from the spirit or scope of the invention as expressed in the following claims.

I claim:

1. A tie rod loosener and puller comprising a shank, a shoe on one end of the shank, a head slidably and tiltably mounted on the shank and having a claw extending transversely of the shank, a handle slidably mounted on the shank and a head on the other end of the shank. 10

2. A tie rod puller comprising a shank, a shoe on one end thereof, and a head slidably mounted on the shank and having a loose fit thereon whereby a limited tilting movement of the head is permitted to lock the head in position on said shank, said head having a fork at one end thereof. 15

3. A tie rod puller comprising a shank, a shoe

on one end thereof, a head slidably mounted on the shank and having a loose fit thereon whereby a limited tilting movement of the head is permitted to lock the head in position on said shank, 5 said head having a fork at one end thereof, an abutment on the shank and a handle slidably mounted on the shank between the head and the abutment.

4. A tie rod puller comprising a shank, a shoe on one end thereof, and a head, having an opening therethrough and slidably mounted on the shank and having a loose fit thereon whereby a limited tilting movement of the head is permitted, said head having means thereon for engaging and pulling a tie rod, said head opening having edges adapted to bite into the shank and hold the head as the shank is operated to pull the tie rod. 10
